UNITED STATES PATENT OFFICE.

EDWARD E. ARNOLD, OF GREENE, COVENTRY, RHODE ISLAND, ASSIGNEE TO NITROGEN PRODUCTS COMPANY, OF PROVIDENCE, RHODE ISLAND, A CORPORATION OF RHODE ISLAND.

SYSTEM FOR RECOVERING CYANIDS AND THE LIKE FROM CYANID-BEARING MATERIAL.

1,314,236.

Specification of Letters Patent. Patented Aug. 26, 1919.

Application filed February 16, 1918. Serial No. 217,484.

To all whom it may concern:

Be it known that I, EDWARD E. ARNOLD, a citizen of the United States, residing at the village of Greene, town of Coventry, in the county of Kent and State of Rhode Island, have invented certain new and useful Improvements in Systems for Recovering Cyanids and the like from Cyanid-Bearing Material, of which the following is a specification.

This invention relates to an improved system for recovering alkali metal cyanid and the like from material which contains, intimately mixed with said cyanid, a material from which the cyanid is to be separated, the invention having for one of its principal objects the effecting of economies in time and in apparatus needed for the extraction and recovery of, for example, sodium cyanid from material containing such cyanid intimately mixed with other substances, such as sodium carbonate. Another object of my invention is to provide apparatus for economically handling a volatilizable solvent, especially as regards its application to the material to be treated, whereby to more efficaciously dissolve the solute, and as regards speeding up or accelerating the subsequent volatilization of such solvent.

I further aim to effect economies in converting the solvent from its gaseous to its liquid phase, and in the time hitherto lost in eliminating occluded solvent from the pores or interstices of the leached or lixiviated mass, after the bulk of the solvent has been withdrawn.

These and other objects of my invention will be hereinafter referred to and the novel combination of means and elements comprised in my improved apparatus, will be more particularly pointed out in the claims appended hereto.

In the drawings, which form parts hereof and in which like reference characters designate like parts throughout the several views, I have exemplified a preferred apparatus in which the process (described and claimed in my co-pending application Serial No. 264,924, filed Dec. 2, 1918, as a division hereof) may be effectuated, and I have herein described the preferred mode of effectuating said process in said apparatus; but as

I am aware of various changes and modifications which may be made both in said process and apparatus, I desire to be limited only by the scope of the claims.

Referring to the drawings:

Figure 1 is a diagrammatic representation of a preferred embodiment of my lixiviating and evaporating system.

Fig. 2 is a front elevation, partly broken away, of, and more fully showing, the lixiviator which appears in the diagrammatic representation aforesaid.

Fig. 3 is a vertical detail section, taken on the line III—III of Fig. 2.

Fig. 3^a is a fragmentary detail section, taken on the line III^a—III^a of Fig. 3.

Fig. 4 is a section taken on line IV—IV of Fig. 3; and showing in plan the locking- or hook-plate for the closure or plug of the lixiviator; and

Fig. 5 is a front elevation of the condenser, the latter being partly broken away to show pipe connections.

In the U. S. patent to John E. Bucher, No. 1,120,682, dated December 15, 1914, there is disclosed a process for forming alkali metal cyanogen compounds, such as sodium cyanid; the material in which the cyanogen compound forming reaction is to be effected, being preferably, although not necessarily, briqueted. This material comprises a substance capable of acting as the source of the base of the cyanogen compound to be formed, ³⁵ e. g., sodium carbonate, intimately mixed with suitable carbonaceous material, such as powdered coke, charcoal, or the like, or a mixture of such carbonaceous material.

There is also preferably present in said mass, catalytic material, such as finely divided iron or the like, and after these materials have been briqueted (or not, as the case may be), they are subjected to nitrogen gas, or to a gas such as producer gas, comprising nitrogen, and also to heat.

The temperature at which the reaction may be effected may be considerably varied, but is preferably in the neighborhood of 1000° C.

In the herein-described process, the cyanized material resulting from this or a similar reaction, is preferably leached or lixiviated with a volatilizable solvent, such as

liquid ammonia, which solvent should preferably be capable of extracting or selectively removing the alkali cyanid from the other solid reaction residues.

5 I make no claim herein to the discovery of this preferred solvent, *per se*, and in general do not desire to be limited to the solvent specified.

I also do not desire to be limited in any 10 way to the mode of initially producing the cyanogen compound sought, the present invention being concerned more especially with an improved method of handling a solvent of the character in question whereby, 15 in one aspect of my invention, to expeditiously extract alkali cyanid from substances from which it otherwise is difficultly separated.

Referring now to Fig. 1, let it be assumed 20 that the extractor or lixiviator, L, has been charged with cyanid bearing material, such as the briquets aforesaid. This receptacle is in connection through pipes 1 and 2 with a receiver R. This latter may initially be 25 charged with the solvent in its liquid phase, and a valve a controls the flow of the liquid from said receiver to the extractor.

The receiver is connected with a suitable condenser C, by means of a pipe 3 in which 30 is a valve b, and a by-pass 4 containing suitable purging apparatus O, hereinafter referred to, connects the sections of pipe 3 disposed upon opposite sides of valve b. It is also preferable to provide a valve c in 35 the by-pass 4. The condenser has connected thereto a pipe 5, preferably of somewhat larger size, in which pipe there is also preferably disposed a valve d; the pipe 5 in turn being connected to a riser or pipe 6. 40 A suitable pump or compressor P, may have one end thereof connected as at 7 with the riser aforesaid, while a connection or pipe 8 at the other end of said compressor connects with the pipe 5 adjacent to the condenser.

45 Pipe 6, shown in Fig. 1 as an extended riser, although it obviously may be otherwise disposed, preferably as therein a valve e, and for convenience of description the section of the riser below valve e has 50 been designated 6'.

In the figure it will be observed that a connection 9 is provided between the upper end of the extractor and the lower end of the pipe 6, and in this connection there is 55 located a valve f. The pipe 1, previously referred to, may conveniently be extended up to the bottom of the leaching tank L', and, in order to vent the gas from this tank when the latter is being filled, a connection 60 10 is provided between the upper side of said tank and the riser 6.

Extending down from the opposite side of the tank L', is a pipe 11 from which laterally extends a pipe 12 at the end of which

is located a vacuum pump P''. A pipe 13, 65 connects the lower end of the lixiviator with pipe 12; pipe 13 having therein a valve g, and the pipe 12 having a valve h therein, between pump P'' and pipe 13.

Immediately below the connection of the 70 pipe 14 with pipe 11, and in the latter, I have shown a valve j, and the lower end of pipe 11 is in connection with a pipe section designated 15. From this latter extends up a pipe 16, which is disposed at 75 the right hand end of the evaporator, as shown in Fig. 1; pipe 16 being connected to said end of the evaporator via pipe 17.

A valve k is located in pipe 17, and the upper end of the pipe 16 is in connection 80 with a pipe 18 which extends between the lixiviator and a heating coil or super-heater S. To the left of the connection of pipe 16 with pipe 18 is valve l, and the left hand end of pipe 18, adjacent the lixiviator, 85 has connected thereto a pipe or conduit 19, which in turn connects with the riser section 6'. In connection 19 there is preferably located a valve m. The super-heater S is connected at its lower extremity by a pipe 90 20 with a pipe 21-21', which extends up from the right hand end of pipe 15 to the pipe 2 aforesaid, as shown. A connection 22 opposite the pipe 20 places pipe 21 in connection with a gas tank or reservoir T, and 95 the latter is in turn connected with a compression pump P', by a pipe 23.

The compression pump is in connection with a part of the condenser, as shown in Fig. 5; a pipe 24 being provided for this 100 purpose. In the upper end of the pipe 21' I preferably locate a valve n, which, as hereinafter described, controls the flow of gas from the tank T direct to the evaporator. A valve o, preferably at the upper end of 105 pipe 21, similarly controls the flow of said gas into the pipe 2.

I also prefer to provide a valve p in pipe 1 above the connection of pipe 2 with the latter and a valve q in the pipe 11 leading 110 down from the re-leaching tank, below the connection of pipe 12 with said pipe 11. In pipe 24 is a valve r which may be closed when the purging apparatus O is in use, on account of the backing up of liquid in 115 the condenser coils at such time.

Ammonia may be introduced into the system, either in liquid form directly into the receiver, by removing the plug 27 of the latter,—or, in gaseous form through the 120 same pipe, 28, through which nitrogen may be supplied; valve s controlling the flow of gas through this pipe.

My invention also preferably involves the provision of a suitable agitating or stirring 125 device 29 in the evaporator; this device being preferably driven by a worm and wheel drive 29' whereby to both facilitate the

complete volatilization of solvent from the cyanid crystallizing out in the evaporator,—when the steam jacket of the latter, or its equivalent, is in operation,—and, also, in 5 manner hereinafter referred to, to favor the formation of fine crystals of said cyanid. Indeed, if the apparatus be not provided with an agitating device, the cyanid, when operating on a large scale, will frequently 10 solidify into a massive block or cake which can only be removed or handled with difficulty.

When the product is in the form of fine 15 crystals or relatively small masses, it can be removed from the evaporator through a suitable opening; the latter normally being plugged as at 30.

The openings through which the preferably briquetted charge is introduced into and 20 discharged from the lixiviator are correspondingly plugged as at 31 and 32.

A few details of the apparatus will now be considered before discussing the operation 25 of the system as a whole.

The lixiviator, as shown in some detail in Fig. 2, preferably comprises a cylindrical container 33, which is provided with a steam jacket 34; live steam being introduced into the latter, as desired, through a pipe 35, and 30 the exhaust steam passing out by way of a pipe 36.

It may be here noted that all of the various receptacles, their plugs or closures, and 35 connections should be adapted to withstand reasonably high pressures; pressures of 150 pounds to the inch, or more, being frequently attained in the lixiviator and other parts of the system. Thus, the plug 32 above referred to, is preferably, as shown in detail 40 in Fig. 3, received into a close fitting aperture in the head 37 of the lixiviator, suitable provisions being made, as shown, for insuring a gas-tight closure; the plug being retained firmly in position by backing out 45 its screw 38 against a hook- or retaining-plate 39, to place the bolts 40' of the latter under tension.

When the screw 38 is reversely turned, or slackened, plate 39 may be rotated arrowwise, as viewed in Fig. 4, to permit the 50 plug 32 and its screw to be withdrawn.

The head 37 is provided with a filter block 40 through which the cyanid containing solvent passes, to free it from any pulv 55 erulent material in the charge being leached; and, for convenience, this block may be secured in position by pouring molten lead or the like therearound, as at 41; a sleeve 42 being driven into a suitable recess 60 in the head to provide an inner wall for the retaining material.

The filter block may be made of any suitable material, and rests upon annular ribs 43, which project upwardly from the bottom

of the recess in the head in which said block 65 is located, so as to provide below the filter block a series of channels 44. As shown in Fig. 3^a, the channels 44 are in connection with each other and with the pipe 13, which may be tapped into the head. 70

At the upper end of the lixiviator is a head 45, similar to that just described, except that it is not provided with the cylindrical extension 37', since, obviously, no filter block is needed therein. 75

The heads 37 and 45 are held by bolts 46, firmly in engagement with annular flanges 47, secured as at 47' to the respective ends of the casing 33; and gas-tight connections are made between these rings and their heads 80 by gaskets 48.

It may be well at this point to consider a further detail, before discussing the mode of operation of the apparatus, and the steps of the process which may be carried out by 85 means of such apparatus.

As shown in Fig. 5 the condenser C may comprise a coil 49, preferably although not necessarily of somewhat flattened tubing to allow the condensed ammonia to flow down 90 therethrough, while leaving a space 50 thereabove in the tubing, to permit of gases in this space being drawn off through the pipe 24, as shown. Suitable refrigerating fluid 52 may be circulated through the condenser 95 as by means of pipes 53 and 54 and the liquid ammonia passes off from the condenser through the pipe 3 as above described.

The operation of the system is as follows:

Assume that the lixiviator is cold and 100 has been charged with alkali metal cyanid bearing material; that the receiver contains the solvent to be employed, in liquid form, e. g., liquid ammonia; and that the various valves in the system have all been closed 105 with the exception of valves *g*, *h*, *q* and *i*.

The vacuum pump *P'* is now started, to 110 exhaust the air from the lixiviator, evaporator and, if the leaching tank be provided, as is to be preferred, it also, together with the various connections thereto, will be correspondingly exhausted.

If desired, in order to make the removal of atmospheric oxygen more complete, the valve *o* may be opened, admitting compressed nitrogen gas, or mixed nitrogen and gaseous ammonia, from the gas tank *T*, which passes up through the pipe 21, to the pipe 2, and thence into the leaching tank, extractor and evaporator. Valve *o* may then 115 be closed and the nitrogen removed from these several receptacles by the vacuum pump; any gaseous ammonia present in this nitrogen being absorbed in the absorber or scrubber *A*. 120

Valves *g*, *h*, *q* and *i* are now closed and valve *a* is opened to admit liquid ammonia, via pipes 2 and 1, to the lixiviator. After 125

the latter has been filled, valve *a* is closed, and valves *g* and *o* may be opened, so that compressed gas flows into the top of the lixiviator and drives the liquid ammonia 5 through pipes 13 and 12, and up through pipe 11, to the releaching tank.

Valves *g* and *o* are now closed and valve *p* is opened to permit the solvent (partially saturated with alkali cyanid) in tank *L'*, 10 to flow down by gravity, into the lixiviator, whereby to more nearly complete the removal of alkali metal cyanid, cyanamid, or the like, from the lixiviator. Valves *f* and *d* may be cracked to relieve the gas pressure 15 in the lixiviator, if this tends to prevent a rapid discharge of liquid from the tank *L'*.

The above circulating operation may, if desired, be repeated several times in order to more nearly saturate the solvent. If the 20 charge of material in the extractor is particularly rich in cyanid; it may be necessary to supply additional liquid ammonia from the receiver,—the saturated solution, first being drawn off into the evaporator, by 25 opening the valves *g*, *q* and *i*.

Should sufficient ammonia evaporate at any time to prevent the proper transfer of the solvent up through the pipe 11 to the re-leaching tank, in the manner described, the 30 latter may be exhausted, by operating the compressor *P*, or even the smaller compressor *P'*, for a short time.

Assuming now that the evaporator has been properly charged with quite well saturated solution; the problem then arises how best to speedily eliminate the liquid ammonia, or the like, occluded in the pores and interstices of the mass in the lixiviator. This occluded liquid is considerable in 40 quantity and evaporates but slowly, even though steam be turned into the jacket of the lixiviator, on account of the poor heat-conductive qualities of the mass in the latter. It has hitherto, therefore, proven to be a 45 serious problem how to shorten the time required for the removal of this occluded liquid, and the solution of this problem is one of the objects of the present invention.

Another object of the invention concerns 50 the proper and yet reasonably rapid evaporation of liquid in the evaporator. On account of the fact that the mass being treated, at least initially, in this receptacle, is wholly liquid, it would not except for the difficulty 55 hereinbelow pointed out, involve a serious problem to speedily evaporate such liquid by means of steam supplied to the evaporator steam jacket. The difficulty is, however, that this heat is largely supplied to the 60 bottom and sides of the liquid mass, which is of course a readily volatilizable one, and the vapor formed rises in the form of bubbles to the surface of the liquid, where it bursts through, entraining the cyanid or the

like, and carrying the latter along through 65 the conduit through which the vapor escapes, until it causes considerable trouble in the piping and especially at the valves, by reason of its accumulation at such points. It is for this reason that I prefer to provide 70 an extended riser, such as that designated 6', through which the generated gas may escape. This difficulty may, however, be further and more nearly completely overcome by not starting the steam jacket of the 75 evaporator into operation until much of the liquid in said evaporator has been driven off by the passage of warm gas over the liquid surface.

This gas may be any suitable one which 80 will not injure the product or solvent, and the inert gas nitrogen, being entirely innocuous, lends itself readily to the purpose.

I do not however desire to be limited to this, since various gases may be employed, 85 or even mixtures of gases.

Thus, as ammonia gas is evolved in the evaporator, it, obviously, is available for use as a heat medium; and indeed, as will be pointed out hereinafter, when, for 90 example, nitrogen gas is thus used in the system, it becomes intermingled with the gas evolved upon the evaporation of the solvent.

Referring again to Fig. 1, therefore, the 95 superheater *S*, as it may for convenience be termed, is started into operation, and, all other valves being closed, the below mentioned valves will be opened:

Gas will pass from the tank *T* through 100 the connections 22 and 20 to the superheater and thence via pipes 18 and 16 to pipe 17, and also to pipe 15, the lower end of pipe 11, and connection 14, to the respective ends 105 of the evaporator, the valves *k*, *j* and *i* being open at such time.

By proper adjustment of valves *j*, *i* and *k*, the flow of warm gas into the opposite ends of the evaporator, may be adjusted, so that a substantially equal flow may be obtained; said gas, together with the vaporous ammonia or the like, given off at the surface of the body of liquid in the evaporator, passing up through the riser 6', and as it is usually preferred to direct this warm gas 115 through the lixiviator to hasten the evaporation of occluded liquid therein, the valve *e* may be closed, or nearly closed, as desired, and the valves *m* and *f* are opened. The expression "warm gas," above mentioned, is 120 intended to be used as a relative term which contemplates that the temperature of the gas in question is rather materially above that at which the solvent copiously volatilizes.

Normally during the just described operation, the valve *d* may be open, and, the compressor being idle, this will prevent the flow of gas through connections 7 and 8.

However, the pressure of gas generated by the evaporation of liquid from the receptacles L and E, will normally be sufficient to enable the condensation of said gas in the condenser; whence the liquid solvent, now free from cyanid, may pass directly down into the receptacle R.

By the procedure above set forth, not only is the volatilization of liquid in the evaporator hastened, but there is a markedly less tendency for the carrying over or up of cyanid. Also the evaporation of the occluded liquid solvent in the lixiviator is greatly expedited.

15 If at any time the rate of volatilization in the evaporator becomes excessive, either the heat imparted by the superheater may be reduced, or the valve *n* may be opened and relatively cool gas admitted to the 20 streams of warm gas entering the evaporator; this cool gas passing down through pipe 21' and entering pipes 15 and 16.

When the liquid in the receptacle L has been completely removed, as by this procedure it will be in a comparatively short 25 time, the valve *e* may be opened and valves *f* and *m* closed, so that the gas leaving the evaporator will pass directly up through the riser section 6 without entering the lixiviator.

30 If for any reason, as on account of the nature of the charge introduced into the lixiviator, difficulty should be encountered in removing the occluded liquid from said charge within a reasonable time, evaporation thereof can be speeded up by opening valve *l*, and closing the valve *m*, whereby to admit warmer gas directly to the lixiviator; this, together with the heat at such time supplied by means of the steam jacket of the lixiviator, very speedily evaporating the residual occluded liquid.

35 After evaporation has been so far reduced that the pressure generated in the condenser is not sufficient to effectively enable this apparatus to perform its function, the valve *d*, if desired, may be closed and the compressor P started. This exhausts the gases from the extractor and evaporator, and as it will 40 frequently be necessary to gain access to the former sooner than the latter, the valves *m*, *e* and *q* (and if desired *p* and *g*) may be closed for a short time, to enable the compressor to exert its full effect upon the gas 45 in the lixiviator, to produce a reasonably high vacuum therein.

After this has been accomplished the valve *f* may be closed and the valve *e* opened to allow the compressor to act wholly upon 50 the evaporator, in like fashion.

When all of the occluded liquid in the lixiviator has been removed from the charge therein, all valved connections thereto should be closed, and the plug 32 in the head

37, may be withdrawn, to remove the charge. 65 At such time the said charge, if the operation has been properly conducted, will be perfectly dry, and have at most therein but substantially a trace of cyanid.

The gas present in the space 50, above the 70 condensed fluid flowing down through the condenser, may be tapped off continuously or intermittently as desired through the pipe 24, through the operation of the compression pump P' which delivers said gas 75 under pressure to the gas tank T.

Thus, if nitrogen be initially supplied from tank T to the system, this nitrogen will be returned to said tank, and unless some special apparatus be provided for removing the ammonia gas mixed therewith, 80 some of this latter gas also will pass through the pump P' into the gas tank. Under a system such as I have described however there is no objection to this, and in so far as 85 the system is concerned, it may be operated substantially as well with ammonia gas alone.

On account of the fact however that, as above noted, such a relatively inexpensive 90 gas as nitrogen, permits of its use for the purpose of sweeping out traces of atmospheric oxygen or the like, and as it is not only cheaper than ammonia, but also equally harmless to the process, I prefer to use it, 95 in manner aforesaid. After the system has been in operation for some time, the gas thus used for sweeping out purposes, will comprise a mixture of nitrogen and ammonia, and to prevent loss of this latter, the 100 absorber A is connected to the delivery end of the vacuum pump P.

As various impurities are, during the course of an extended operation of apparatus of this description, apt to accumulate 105 in the solvent employed, it is desirable to provide means to remove such impurities from time to time. To this end, the purging apparatus O is disposed in the by-pass 110 4, so that the liquid passing from the condenser to the receiver, instead of passing directly to the latter through pipe 3, may, by the closing of valve *b* and opening of valve *c*, be forced to pass through said purging apparatus. At such time, with the arrangement shown, it is preferable not to operate the pump P', on account of the rise in level 115 of liquid within condenser coil.

I particularly desire to emphasize the importance of using a suitable gaseous medium 120 as a means for conveying heat to the interior of the mass in the lixiviator, as a means for effectively removing occluded liquid therefrom. The importance of thus speeding up this phase of the operation will be 125 appreciated upon consideration of the fact that by thus very materially cutting down the time required for the removal of this

6
liquid from said mass, the apparatus can in any given period of time handle the output of a very much larger cyanizing unit; so that a marked economy is effected, not only 5 in time, but in the cost of installation, space occupied by the plant, and other costly items.

In like fashion, the speeding up of the 10 rate of evaporation of liquid in the evaporator through the practical overcoming of the difficulty above noted, similarly effects 15 worth-while economies of operation.

I also desire to direct attention to the 15 utilization, in the preferred mode of effectuating my process, of the still relatively warm gases passing off from the evaporator, as a means for hastening the volatilization 20 of occluded liquid in the lixiviator.

The system as a whole, moreover, is a very 20 flexible one and adapts itself to varying conditions; and while all of the features shown therein are by no means essential thereto, in so far as the broadest aspects 25 of my invention are concerned, they nevertheless add to the efficiency of the system as a whole. Thus, while I am aware that it is not necessary to provide a leaching tank in order to with ease nearly completely 30 saturate the solvent with its solute; still the combination of this tank with the lixiviator and associated parts, permits of the solvent being exceedingly well circulated or flushed 35 through the charge to be leached, and this without loss of the solvent, and with very appreciable gain in recovering cyanid from all parts of the leached mass. The importance of this will be seen when it is pointed out that if one merely allows liquid 40 ammonia, for example, to run into the lixiviator, and even though it be allowed to stand in this receptacle for 20 or 30 minutes, when it has been drawn off, and the briquets or the like are analyzed to ascertain the 45 cyanid content remaining therein, it will be found usually that there is a very much larger percentage of cyanid in the briquets at the top of the charge than in those in the center; and that for some reason, the briquets in the lower part of the charge are 50 richer in cyanid than those in the center, although not normally so rich as those at the top.

The combination of the jets or currents of warm gas over the surface of the liquid 55 in the evaporator, with the means for applying heat superficially to this receptacle, *e. g.*, the steam jacket, is also of importance, in that a large part of the liquid may be first removed, working from the surface of 60 the liquid down, so to speak, and after much of this liquid has thus been evaporated, the bringing into play of the steam jacket or the like, accelerates the last portion of this operation, which otherwise is quite slow.

The effect of the superficial heating of the 65 charge in the evaporator, when much of the liquid in the latter has been driven off and the mass is approaching its crystalline condition, has an important bearing upon the ultimate condition of the recovered cyanid; 70 since at such time, the steam jacket is preferably in operation and the agitating apparatus is being driven in a direction to churn or thoroughly agitate the mass, but on account of the refrigerating effect of the volatilizing solvent, there is a tendency for this 75 mass, especially as it becomes thick with crystals, to cake or solidify in portions thereof and thereby to resist the action of the agitator. This calls for expenditure of 80 more work in driving the latter, and the product is apt not to be as finely divided as might be desired. On the other hand the flow of warm gas over the surface of the charge at such time, supplements the 85 heat imparted to the charge by the walls of the receptacle and tends to maintain the temperature of the charge as a whole, more nearly uniform; with the result that the product is improved and the expenditure 90 of energy in turning the agitating paddles is reduced.

Finally, the evaporation of solvent in the 95 above described manner, coupled with the utilization of the pressure so obtained to enable the condensation of gas or vapor in the condenser, and this especially for that part of the time during which the condenser is idle, results in great fuel economy, for 100 the following reason: With this method the 100 energy for forcing the ammonia from the evaporator to the condenser coils, and for producing the pressure at which the ammonia will condense in the coils, has its 105 source in the superheater and in the heat of the steam in the steam jacket or jackets, and all of this heat is used to produce the desired results.

As above noted, when substantially all of 110 the liquid ammonia is vaporized, the evaporator is left full of gaseous ammonia, which must be withdrawn and since it must be delivered to the condenser coils under high pressure, a compressor is required; but in this case it need be but a relatively small 115 one. Indeed, it is even possible to omit the compressor P, relatively small though it is, and rely upon the pump P' to remove this residual gas; it being understood, however, that in such case this remaining gas will not 120 be condensed but will be delivered to the tank T under pressure, ready for return to the system through the superheater, or otherwise, as desired.

If the gas delivered to the tank T be not 125 allowed to cool, it will normally be quite warm, in most cases, after being compressed.

The above described system has the fur-

ther advantage that if liquid ammonia be the solvent used, as is to be preferred,— only anhydrous ammonia need be used as is to be desired where substantially pure cyanid is the product sought.

Having thus described my invention, what I claim is:

1. A system for recovering alkali cyanid from material bearing the same, which comprises a lixiviator in which said material is leached, an evaporator to receive the cyanid-containing solution produced in said lixiviator, means to impart heat to said solution to volatilize the solvent thereof, and connections co-acting with said lixiviator to conduct warm gas from said evaporator through the leached material, to volatilize the occluded solvent in the pores of the latter.
2. A system for recovering alkali cyanid from material bearing the same, which comprises a lixiviator in which said material is leached, an evaporator to receive the cyanid-containing solution produced in said lixiviator, means to impart heat to said evaporator to volatilize the solvent therein, heating means for said lixiviator, and connections co-acting with said lixiviator to conduct warm gas through the leached material, to volatilize the occluded solvent in the pores of the latter.
3. A system for recovering alkali cyanid from material bearing the same, which comprises a lixiviator in which said material is leached, means for removing solvent from and returning such removed solvent to said lixiviator, an evaporator to receive the cyanid-containing solution produced in said lixiviator, and means to promote rapid volatilization of the solvent in said evaporator and also of that occluded in the pores of the leached material.
4. A system for recovering alkali cyanid from material bearing the same, which comprises a lixiviator in which said material is leached, an evaporator to receive the cyanid-containing solution produced in said lixiviator, heating means for said evaporator and air-tight connections, for excluding air, co-acting with said lixiviator to conduct warm gas through the leached material, to volatilize the residual occluded solvent in the pores of said leached material.
5. A system for recovering alkali cyanid from porous material bearing the same, which comprises a lixiviator in which said material is leached, an evaporator to receive the cyanid containing solution produced in said lixiviator, and means for supplying a gaseous heating medium successively to the evaporator, when the latter is charged, and to the lixiviator, when said solution has been discharged therefrom, to volatilize solvent

in the evaporator and residual solvent occluded in the pores of the leached material.

6. A system for recovering alkali cyanid from porous material bearing the same, which comprises a lixiviator in which said material is leached, means to receive liquid drawn off from said lixiviator, and means to volatilize residual occluded solvent from the pores of said material by the passage of warm gas through said pores, said means including connections for supplying the gas to said lixiviator and means for elevating the temperature and pressure of said gas previous to its introduction into said lixiviator.

7. A system for recovering alkali cyanid from porous material bearing the same, which comprises a lixiviator in which said material is leached, means to receive liquid drawn off from said lixiviator, and means to volatilize residual occluded solvent from the pores of said material by the passage of warm gas through said pores, said means including connections for supplying an innocuous gas to said lixiviator and means for elevating the temperature of said gas.

8. A system for recovering alkali cyanid from porous material bearing the same, which comprises a lixiviator in which said material is leached, means to receive liquid drawn off from said lixiviator, and means to volatilize residual occluded solvent from the pores of said material by the passage of warm gas through said pores, said means including connections for supplying an innocuous gas to said lixiviator and means to compress the gas passing off from said lixiviator preparatory to the return of a portion at least of such gas to said supplying connections.

9. A system for recovering alkali cyanid from porous material bearing the same, which comprises a lixiviator in which said material is leached, means to receive the solvent drawn off from said lixiviator, heating means to volatilize the solvent so drawn off, means to collect substantially all and condense a part of the volatilized solvent, and means for delivering a part of said volatilized solvent, while warm, again to said lixiviator to evaporate residual solvent occluded in the pores of the leached material.

10. A system for recovering alkali cyanid from porous material bearing the same, which comprises a lixiviator in which said material is leached, means to receive the solvent drawn off from said lixiviator, heating means to volatilize the solvent so drawn off, means to collect and compress substantially all of the volatilized solvent, means to condense a part of said solvent, and means to deliver an uncondensed part of said solvent under pressure and while warm, again to both said lixiviator, to evaporate residual

solvent occluded in the pores of the leached material, and to said evaporator, to supplement the action of said heating means.

11. A system for recovering alkali cyanid 5 from material bearing the same, which comprises means for leaching said material with liquid ammonia to form a solution of cyanid in said ammonia, means to supply hot gas to the upper surface of said solution 10 to there evaporate said ammonia, and means to collect and condense a part of the gaseous material leaving said surface, said last

mentioned means having a portion thereof connected to said gas supplying means to permit the flow of a part of the gaseous material, last aforesaid, therethrough to said supplying means to form a part at least of the gas supplied.

In testimony whereof I have affixed my signature, in the presence of two witnesses. 20

EDWARD E. ARNOLD.

Witnesses:

HAROLD E. TRUE,
HOWARD C. RIPLEY.
